(57) **CLAIM**

The ornamental design for an electrical contact terminal as
shown and described.

DESCRIPTION

FIG. 1 is a perspective view of an electrical contact terminal
showing our new design;

FIG. 2 is a side elevational view thereof;

FIG. 3 is a front elevational view thereof;

FIG. 4 is a bottom plan view thereof; and,

FIG. 5 is another perspective view thereof, shown in a
different angle. The broken lines in the drawings depict
portions of the 'electronic contact terminal' that form no part
of the claimed design.
